UNITED STATES PATENT OFFICE.

DWIGHT MURPHY, OF PITTSBURGH, PENNSYLVANIA, ASSIGNOR TO P. H. MURPHY COMPANY, OF PARNASSUS, PENNSYLVANIA, A CORPORATION OF PENNSYLVANIA.

CAR-ROOF.

1,161,508.

Specification of Letters Patent. Patented Nov. 23, 1915.

Application filed August 20, 1915. Serial No. 46,470.

To all whom it may concern:

Be it known that I, DWIGHT MURPHY, a citizen of the United States, and a resident of the city of Pittsburgh, in the county of Allegheny and State of Pennsylvania, have invented a new and useful Improvement in Car-Roofs, of which the following is a specification.

This invention relates to metal car roofs of a well known type in which the roof sheets extend crosswise of the car and are connected at their side margins by upstanding seams. In this type of roof, the sheets are usually held by hood caps or fasteners which are secured to the sides of the car and overlap and embrace end portions of the seams. Heretofore such hood caps or fasteners have been made in a single piece without adequate provision for more than slight movement of the seams longitudinally of the car.

The object of the present invention is to permit the roof sheets to move to a limited extent to accommodate themselves to the racking and weaving of the car body and to adapt the hood caps or fasteners so that they will follow the movements of the seam longitudinally of the car.

The invention consists principally in making the hood caps or fasteners in two parts, one of which spans the roof seam and is adapted to slide endwise of the car with said seam without becoming unfastened from the other part.

It also consists in the construction and arrangement of the parts hereinafter described and claimed.

In the accompanying drawings, in which like symbols are used to designate like parts wherever they appear, Figure 1 is a side elevation of the eaves portion of a car; Fig. 2 is a cross-section of the same on the line 2-2 of Fig. 1; Figs. 3 and 4 are inner face views of the retaining clip and hood piece, respectively.

My invention is shown in the drawings applied to a car comprising side plates 1 to which the side sheathing 2 is secured. Roof sheathing 3 is nailed to the top of the car and at the eaves rests directly upon the side plate and side sheathing. A shallow rabbet is cut in the top side of the eaves edge of the roof boards within which rests the rebent end 4 of the flashing strip 5. The

flashing strip is bent down over the fascia board and securely nailed.

Supported upon the roof sheathing 3 are metal roof sheets 6 having rebent ends 7, which interlock with the rebent ends 4 of metal flashing strips 5. The roof sheets are connected by interlocking upstanding seams 7, which are made by overlapping the rebent side marginal portions of the sheets.

The hood cap fasteners comprise two parts. One of these parts, hereinafter called the hood portion 8, overlaps and embraces the end of a roof seam and has a portion 9, that extends downwardly alongside of the fascia. The lower end of this downwardly extending portion has an outwardly or horizontally extending portion 10 at the end of which is an additional downward extension 11. This hood portion has elongated horizontal extensions 12 on each side thereof extending longitudinally of the car at a slight distance inward from the eaves of the car so as to rest upon or slightly above the roof sheets. The second piece or member of the fastener is a wide yoke-shaped clip 13 provided with a bolt-hole 14 in its lower portion and having the ends of its arms 15, bent inwardly and substantially horizontally so as to overlie the longitudinally extending arms 12 of the hood piece.

In the body portion of the yoke is an elongated horizontal slot 16 of sufficient width to admit the depending part 9 of the hood portion 8 and allow it to slide therein. The clip 13 is secured to the side of the car by a carriage bolt 17 which extends through the fascia, sheathing and side plate of the car and is preferably prevented from pivoting or tilting by nails 18, one on each side of the bolt. The retaining clip is also provided with inwardly projecting spacing lugs 19, which also tend to prevent it from pivoting or tilting and thereby prevent the mashing of the seams and rebent ends of the flashing and roof sheets. The retaining clip is provided with a semi-circular flange 20 located above its bolt hole 12 and which acts as a watershed for the head of the bolt 17, thus preventing water from running along the bolt and entering the car.

Under some actual service conditions of the roof provided with a socalled "flexible roof", there is a tendency of the sheets to move endwise of the car. Under such con-

ditions, my fasteners permit considerably more movement than has heretofore been practicable. The part which spans the seam moves with the seam, sliding freely in the 5 elongated slot provided therefor in the other part of the fastener which remains fixed to the car.

This invention is applicable to other types of roofs and the construction herein described is capable of considerable modification without departing from my invention. Therefore I do not wish to be restricted to the precise form shown in the 10 drawings.

15 I claim the following as my invention:

1. A fastener for car roof sheets comprising a hood member adapted to cover the end portion of a roof seam, and a member adapted to be secured to the substructure, said 20 members being slidably connected.

2. A fastener for a car roof comprising a member having a portion adapted to embrace a seam, elongated lateral extensions projecting horizontally therefrom, and an 25 elongated extension projecting downwardly and adapted for slidable engagement with a second member.

3. A fastener for car roof sheets comprising two members slidably secured together, 30 one of said members being a bifurcated clip having an elongated slot, and the other member having a portion slidably engag-

ing said slot and a portion adapted to engage a seam and provided with lateral extensions that underlie projecting portions 35 of the bifurcations of said first mentioned member.

4. A fastener for a car roof comprising metal roof sheets connected by upstanding seams, said fastener comprising a hood portion adapted to embrace the seam, said hood portion having a body portion extending downwardly and outwardly and means for 40 movably securing the hood cap to the car.

5. In a car roof, the combination of metal 45 roof sheets extending crosswise of the car and connected by upstanding seams, a fastener comprising a hood portion adapted to embrace the eaves end of the seam, and a retaining clip secured to the car, the retaining clip and hood portion being slidably connected.

6. A retaining clip for a two-piece car roof fastener, said clip having a body portion adapted to be secured to the car, said 55 body portion having spaced fingers at its sides extending upwardly and thence inwardly and also having an elongated slot extending across its body portion adapted to receive the downwardly extending portion of the other member of the fastener.

Signed at New Kensington, Pa., this 13th day of August, 1915.

DWIGHT MURPHY.
